UNITED STATES PATENT OFFICE.

EDMUND C. MORGAN, OF CHICAGO, ILLINOIS, ASSIGNOR TO TITLOW WASTE HEAT POWER COMPANY, OF UNIONTOWN, PENNSYLVANIA, A CORPORATION OF WEST VIRGINIA.

APPARATUS FOR UTILIZING COKE-OVEN HEAT.

1,054,859.

Specification of Letters Patent.

Patented Mar. 4, 1913.

Application filed January 28, 1909. Serial No. 474,641.

To all whom it may concern:

Be it known that I, EDMUND C. MORGAN, a citizen of the United States, residing in Chicago, in the county of Cook and State of Illinois, have invented a new and useful Improvement in Apparatus for Utilizing Coke-Oven Heat, of which the following is a specification.

My invention relates to improvement in apparatus for utilizing coke oven heat and the object of my improvement is to utilize the heat which now goes to waste in the manufacture of coke in beehive and other types of ovens producing coke by the same process as the beehive type of oven. I attain these objects by the mechanism illustrated in the accompanying drawings, of which,

Figure 1 is a vertical section of the apparatus and also shows the outline of the upper part of a beehive oven. Fig. 2 is a plan view of the apparatus showing application to two beehive coke ovens.

Similar letters refer to similar parts throughout the several views.

Mounted on the oven wall by means of suitable standards (A) are suitable steam tight pipes (B), one placed above the other, and to which are connected at right angles the short closed end pipes (C). The passageways in the short pipes (C) communicate with the passageways of the pipes (B). The passageways in the pipes (C) may be closed by means of the valves (D).

Movably mounted above the ovens on a standard or track (F), or other suitable means, is a suitable steam generator (E) which is pivotally connected to the short pipes (C) by means of the arms (G), the ends of which are provided with suitable ground joints which are detachably held in position in a suitable bearing in the short pipes (C) by means of the nuts (H). The steam passageways of the steam generator (E), are connected to the passageways of the short pipes (C) by means of suitable passageways through the arms (G).

The steam generator (E) being pivotally mounted as described is arranged so that at one point in its movement around the pivot it will stand centrally over the opening in the top of the oven, and at another point in its movement around the pivot it will be entirely clear of the opening in the top of the oven, so that the charging

of the ovens may be carried on the same as heretofore.

Mounted on the lower end of the steam generator (E) and made vertically adjustable thereto by means of lever (I) is a ring (J), preferably made of fire brick or some other heat resisting material, the inside of this ring conforming approximately to the size of the opening in the top of the oven and the outside being about the size of the flue in the bottom of the steam generator (E) so that when the ring is resting on the top of the oven, as clearly shown in Fig. 1, the gap between the bottom of the steam generator (E) and the top of the oven is closed, so as to form a continuous flue from the inside of the oven to the top of the steam generator (E).

By the construction shown, the steam generated by the heat from one or more ovens can be carried to any desired point by means of the pipes (B) by methods well known to those skilled in the art. Where a number of generators are connected together in one line, in case it is necessary to repair an oven, or to repair a generator, or to remove a generator entirely and install a new one, it may be done without interruption of the other steam generators in the plant.

Having now explained the principles of my invention and a form of apparatus embodying the same, what I claim as new and desire to secure by Letters Patent, is:

1. In an apparatus for utilizing coke oven heat, the combination of a steam generator having a flue for vertical draft therethrough, and means for supporting said generator above the oven for horizontal movement in an arc and provided with sufficient latitude of movement so that at one point in its movement it is over the opening in the top of the oven and at another point in its arc of movement it is entirely clear of the opening in the top of the oven.

2. In an apparatus for utilizing coke oven heat, a steam generator pivotally mounted above the oven so that at one point in the arc of its horizontal movement around the pivot it is over the opening in the top of the oven, and at the other point in the arc of its movement around the pivot it is entirely clear of the opening in the top of the oven, said generator having a flue for draft therethrough, substantially as described.

3. In an apparatus for utilizing coke oven heat, a steam generator mounted above the oven and means for closing the gap between the flue in the generator and the opening in the top of the oven thus forming a continuous flue from the inside of the coke oven to the top of the generator, substantially as described.
4. In an apparatus for utilizing coke oven heat, two or more coke ovens, each provided with an opening through its top, and two or more steam generators mounted above the ovens for horizontal movement in an arc, the steam space in one generator being connected to the steam space in the other generator by means of suitable passage ways, said generators being movable independently of each other.
5. In an apparatus for utilizing coke oven heat, the combination of two or more coke ovens, each provided with a steam generator mounted above it for horizontal movement in an arc, the steam spaces of the generators being connected together by means of suitable passageways, said generators being movable independently of each other, substantially as described.
6. In an apparatus for utilizing coke oven heat, the combination of two or more coke ovens, each provided with a steam generator mounted above it for movement in an arc, the steam spaces of the generators being connected together by means of suitable passageways, said generators being horizontally movable independently of each other, means for shutting off the passageways from any one of the generators independently of the others, substantially as described.
7. In apparatus for utilizing coke oven heat, the combination with a supply pipe, of a steam pipe, a coke oven, and a steam generator having a flue for vertical draft therethrough and being pivotally connected to said supply and steam pipes and capable of being moved in an arc horizontally over the upper opening in the oven or away from it.
8. In apparatus for utilizing coke oven heat, the combination with a coke oven, of a steam generator mounted above the same for movement in an arc and having a flue vertically arranged to increase the draft through said coke oven.
9. In apparatus for utilizing coke oven heat, the combination of a steam generator mounted above the oven, and means carried by the oven for closing the gap between the flue in the generator and the opening in the top of the oven.
10. In apparatus for utilizing coke oven heat, the combination of a steam generator, and a device pivoted to said generator and movable to a position to close the gap between the flue in the generator and the opening in the oven.
11. In apparatus for utilizing coke oven heat, the combination with a steam generator movable to a position over the oven, of a manually operated lever pivoted to said generator, and a ring pivoted to the inner end of said lever and movable by the latter to a position closing the gap between the flue in the generator and the top opening in the oven.
12. In apparatus for utilizing coke oven heat, the combination with a steam generator having portions of the body extending into the flue to increase the heating surface, a supply pipe, a steam pipe, pivotal connections between said generator and said pipes, and means for closing the gap between the flue of said generator and the upper opening in said oven.
13. The combination of a series of coking ovens having openings for the escape of products of combustion, a series of movable receptacles, steam and water mains extending along the series of ovens, and flexible connections extending from each receptacle to said steam and water mains, whereby the receptacles can be shifted independently of each other to and from operative relation to the respective openings from the coking ovens.
14. The combination of a series of coking ovens having openings for the escape of heat and the products of combustion, a series of movable receptacles, steam and water mains extending along the series of ovens, and flexible connections extending from each receptacle to said mains, valve mechanism in such connections adapted to be closed and opened by the movement of the receptacles from and to position over the openings in the coke ovens.
15. In an apparatus for utilizing coke oven heat, the combination of a coke oven, a frame mounted above said coke oven, a steam generator, adapted to receive the heat coming from the trunnel head of the coke oven, mounted on said frame and arranged for horizontal movement, theron, a water supply pipe, a flexible communicating connection between said water supply pipe and said steam generator, a steam pipe and a flexible communicating connection between said steam pipe and said steam generator.
16. In apparatus for utilizing coke oven heat, the combination of two or more coke ovens, and a plurality of steam generators one mounted above each of said ovens for horizontal movement, and suitable passageways affording steam spaces connecting the generators, said generators being movable independently of each other.
17. In apparatus for utilizing coke oven heat, the combination with two or more coke ovens, of a plurality of steam generators one mounted above each of said ovens for horizontal movement, passageways afford-

ing steam spaces connecting the generators, means permitting the horizontal movement of said generators independently of each other, and means for shutting off the passageways from any one of the generators independently of the other.

18. The combination with a coke oven, of a vertical draft steam generator, a device for assisting in supporting said steam generator and directing its horizontal movement, connections permitting said steam generators to be moved over the trunnel heads of the coke oven to receive the heat issuing from the same or to be moved away from the same without substantial leakage of the water supply or of the steam generator.

19. The combination with a coke oven, of a frame mounted above said coke oven, a vertical flue steam generator adapted to receive the heat coming from the trunnel head of the coke oven, said generator being mounted on said frame and arranged for horizontal movement thereon, and steam or water supply pipes for said generator.

20. In an apparatus for utilizing coke oven heat, the combination with a coke oven, a frame mounted above said coke oven, a steam generator adapted to receive the heat coming from the trunnel head of the coke oven, mounted on said frame and arranged for horizontal movement thereon, a water supply pipe, a pivoted communicating connection between said water supply pipe and said steam generator, a steam pipe and a flexible communicating connection between said steam pipe and said generator.

21. In an apparatus for utilizing coke oven heat, the combination of a coke oven, a frame mounted above said coke oven, a steam generator adapted to receive the heat coming from the trunnel head of the coke oven, mounted on said frame and arranged for horizontal movement thereon, a water supply pipe carried on said frame, a flexible communicating connection between said water supply pipe and said steam generator, a steam pipe carried on said frame and a flexible communicating connection between said steam pipe and said generator.

22. In an apparatus for utilizing coke oven heat, the combination with a coke oven, of a frame, and a vertical draft steam generator supported by and movable horizontally on said frame to the position where the generator will receive the heat from the trunnel head of the oven or to a position where it will not receive such heat.

23. The combination with a coke oven of a steam generator, a track for supporting said generator over said oven or away from the same, fixed water supply and steam pipes, and pivoted connections between said

supply pipes and said generator to permit free movement of the latter without leakage.

24. In an apparatus for utilizing coke oven heat, the combination with a coke oven, of a steam generator, a track for slidably supporting said steam generator, water and steam supply pipes, and connections permitting the free movement of said generator on said track over the trunnel head of the oven or away from the same.

25. In an apparatus for utilizing coke oven heat, the combination of two or more coke ovens, each provided with a steam generator mounted above it for horizontal movement in an arc, the steam spaces of the generators being connected together by means of suitable passage-ways, said generators being movable independently of each other.

26. In an apparatus for utilizing coke oven heat, the combination of two or more coke ovens, each provided with a steam generator mounted above it for movement in an arc, the steam spaces of the generators being connected together by means of suitable passage-ways, said generators being horizontally movable independently of each other, means for shutting off the passage ways from any one of the generators independently of the others.

27. In apparatus for utilizing coke oven heat, the combination with a coke oven, of a steam generator mounted above the same for movement in an arc, and having a flue vertically arranged to increase the draft through the coke oven.

28. In an apparatus for utilizing coke oven heat, the combination of a coke oven, a frame mounted above said coke oven, a steam generator, adapted to receive the heat coming from the trunnel head of the coke oven, mounted on said frame and arranged for horizontal movement thereon, a water supply pipe carried in said frame, a flexible communicating connection between said water supply pipe and said steam generator, a steam pipe carried in said frame and a flexible communicating connection between said steam pipe and said steam generator.

29. The combination with a coke oven, of a steam generator, means for carrying said generator when over said oven or when away from the same, fixed water supply and steam supply pipes, a flexible water-tight and steam-tight connection between the said fixed pipes and generator to permit free movement of the latter without leakage.
